INVENTOR:

Dr. Ludwig Dürr

UNITED STATES PATENT OFFICE.

LUDWIG DÜRR, OF FRIEDRICHSHAFEN-ON-THE-BODENSEE, GERMANY, ASSIGNOR TO THE FIRM LUFTSCHIFFBAU ZEPPELIN G. M. B. H., OF FRIEDRICHSHAFEN, GERMANY.

OVERPRESSURE VALVE.

Application filed September 3, 1921. Serial No. 498,585.

To all whom it may concern:

Be it known that I, LUDWIG DÜRR, a citizen of the Republic of Germany, residing at Friedrichshafen-on-the-Bodensee, Germany, have invented certain new and useful Improvements in Overpressure Valves (for which I have filed an application in Germany July 5, 1920), of which the following is a specification.

10 My invention refers to airships and more especially to the safety valves inserted in the walls of the gas cells of airships of the rigid type.

In the gas cells of rigid airships the safety valves are as a rule arranged symmetrically, which results in an equal pressure acting on all the valves. This arrangement, however, involves the disadvantage that each valve requires separate gas exhausts.

20 The present invention allows to discharge the gas of two adjacent cells into a common gas flue. If the valves heretofore used were arranged in adjacent walls of two adjacent cells there would, upon inclination, result 25 different gas pressure, so that, for instance, the lower cell would discharge the gas earlier than the higher one, because a higher gas column is acting on the valve of the lower cell, while on the upper cell there acts a 30 smaller gas column.

It is an object of my invention to avoid these drawbacks. In spite of the different pressures acting on the valves the gas is caused to be discharged simultaneously, the 35 valve discs together with the additional weights combined with these discs creating a higher closing pressure on the valve of the lower cell and a lower pressure on the valve of the upper cell, than corresponds to the 40 normal pressure predetermined by the power of the valve spring. The radially acting component of weight of the disc is taken up by a special supporting device. By suitably selecting the weight of the valve discs provision can be made for adjoining valves to 45 discharge simultaneously at all inclinations of the airship in spite of the different gas pressures. Naturally this arrangement involves the disadvantage that not only the 50 load pressure of the valve disc of the lower cell, in which the gas pressure rises, is altered, but also the pressure of the upper cell in which it is practically independent from the inclination of the airship. Consequently

the upper cell valves blows off at a lower 55 pressure than is required in respect to the tearing strength of the gas cell envelope.

The valves further blow off earlies in the inclined position than in the horizontal, thus causing some loss of gas. It is, however, 60 possible to avoid these inconveniences by influencing the disc of the lower valve by a weight and leaving the loading pressure of the upper valve disc unaltered. This is attained by giving the additional weight the 65 form of a pendulum thus causing this weight to always bear on the lower valve disc.

I prefer using only a single pendulum weight common to both valves of a pair. In order to obtain a normal lift of the valve 70 disc the pendulum weight comes in contact with the disc only at a predetermined small inclination of the airship. Furthermore the weight of the disc of the lower valve acts still towards closing and the weight of the 75 upper disc towards opening their respective valves. These faults, however, remain within limits set by accidental inaccuracies such as differences in the quantity of gas in the 80 different cells and different weight of the supporting gas. However, these inconveniences can be avoided, including the disturbance caused by the gas column which acts upon the valves also in the horizontal 85 position of the airship and which changes somewhat at inclined positions, as also the disturbance arising through the weight of the valve disc in a case where the valves are arranged in the horizontal bottom of the cell. In such cases the pendulum weight must act 90 indirectly, for instance, by means of bent levers or the like.

It is further possible to lessen these faults resulting from the weight of the valve disc by taking this weight into consideration in 95 selecting the pendulum weight.

If a single pendulum weight only is provided for each valve, it can be arranged in such manner that it contacts with the valve disc even in the smallest inclination of the 100 airship. If the distance between the valve disc surface and the pendulum weight is made about equal to one half of the valve lift, the distance will compensate the fault which results from the deviation of the 105 pendulum weight while the valve is lifting.

In the drawings affixed to this specification and forming part thereof an arrange-

ment embodying my invention is illustrated diagrammatically by way of example. In the drawings Figure 1 is an axial longitudinal section through a part of an airship hull.

5 Figure 2 is a longitudinal section of the valves of two adjoining gas cells drawn to a larger scale, the different gas pressures being here compensated by the weight of the valve discs.

10 Figure 3 is a similar view of a modification, the valves being balanced by means of pendulum weights.

Referring to the drawings, the valves are fixed in adjoining end walls *a*, *b* of the gas 15 cells *I*, *II*, respectively, the gases escaping into a common gas flue *c*. Each valve consists of a ring *d* against which is pressed the valve disc *e* by a spring *f* mounted on the hoop *g*. The component *E* directed at 20 right angles to the longitudinal axis of the airship and which is equal to the weight *G* of the valve disc, is taken up by a flexible band *h*. The component *D* acts on the valve of the gas cell *I* against the pressure 25 of the gas column *H*'—*H*, while the component *D* of the valve of gas cell *II* acts in opposite direction to the component of the other valve, i. e. in the direction of the gas pressure. In the horizontal position 30 of the airship the springs *f* which are permanently under the same pressure, will close the valves, because in this case *D* is equal to zero.

In the modification illustrated in Figure 35 3 the valves are again arranged in adjoining end walls *1*¹, *1*² of two gas cells. The valve discs *m*¹ and *m*² are kept closed by tension springs *n*¹ and *n*². A pendulum weight *o* is suspended from a point *q* by a 40 wire or chain *p* and in accordance with the inclinations of the airship will swing free of the upper valve disc and come in contact with the lower valve disc, thereby increasing the valve pressure counteracting the 45 gas pressure.

I wish it to be understood that I do not desire to be limited to the exact details of construction described for obvious modifications will occur to a person skilled in the 50 art.

I claim:

1. An airship comprising a plurality of 55 gas cells, safety valves oppositely arranged in adjoining end walls of said cells, valve discs in said valves and closing springs acting on said discs, the weight of said discs being such that upon inclination of said airship the combined spring and disc pressures suffice to counteract the tendency of 60 the increased gas pressure, of the lower gas cell to open the lower valve.

2. An airship comprising a plurality of 65 gas cells, safety valves oppositely arranged

in adjoining end walls of said cells, valve discs in said valves, closing springs acting 65 on said discs and means extending at right angles to the longitudinal axis of said airship and attached to said discs for holding same, the weight of said discs being such that upon inclination of said airship the 70 combined spring and disc pressure suffices to counteract the tendency of the increased gas pressure, of the lower cell to open the lower valve.

3. An airship comprising a plurality of 75 gas cells, safety valves oppositely arranged in adjoining end walls of said cells, cover discs in said valves, closing springs acting on said discs and a pendulous weight suspended in swinging contact with said discs, 80 whereby upon inclination of said airship said weight will contact with the disc of the lowermost of said valves, the combined spring, disc and weight pressure sufficing to counteract the tendency of the increased 85 gas pressure, of the lower cell to open the lower valve.

4. An airship comprising a plurality of 90 gas cells, safety valves oppositely arranged in adjoining end walls of said cells, cover 95 discs in said valves and closing springs acting on said discs, the weight pressure of said discs being adapted upon inclination of said airship to increase the weight pressure on the lower valve and to decrease the weight pressure on the upper valve sufficiently, substantially to compensate for the difference in gas pressure on both valves resulting from such inclination, thereby providing for substantially simultaneous 100 gas discharge from both said adjacent safety valves.

5. An airship comprising a plurality of 105 gas cells, safety valves oppositely arranged in adjoining end walls of said cells, cover 110 discs in said valves, closing springs acting on said discs and means extending at right angles to the longitudinal axis of said airship and attached to said discs for holding same, the weight pressure of said discs being adapted upon inclination of said airship to increase the weight pressure on the lower valve and to decrease the weight pressure on the upper valve sufficiently, substantially to compensate for the difference 115 in gas pressure on both valves resulting from such inclination, thereby providing for substantially simultaneous gas discharge from both said adjacent safety valves.

In testimony whereof I affix my signature 120 in presence of two witnesses.

DR. LUDWIG DÜRR.
